MANICURING APPLIANCE

Filed July 18, 1930

FIG. 2

INVENTOR
ERNEST SORENY

BY *Frank E. Ward*

ATTORNEY

UNITED STATES PATENT OFFICE

ERNEST SORENY, OF NEW YORK, N. Y.

MANICURING APPLIANCE

Application filed July 18, 1930. Serial No. 468,773.

This invention relates to manicuring appliances and more particularly to holders of tensioned fibrous material for cleaning finger nails.

Usually a person cleans the nails on the hand with a file or other sharp instrument which is liable to cause infection of the sensitive parts of the fingers under the nails or fail to dislodge foreign matter without undue pain. Furthermore, a nail file is not sufficiently flexible or yielding to enter the crevice at the juncture of the nail and quick of the finger to efficiently remove encrusted particles accumulated therebetween. Another difficulty attending the use of a metallic instrument in contact with sensitive skin tissues of the fingers is the probability of aggravating the sensitivity of the nerves terminating under the finger nails to such an extent that the fingers are too sensitive to handle or touch articles.

Therefore, the need of a sufficiently pliable cleaning agent will be readily apparent. In order to manipulate a convenient agent, such as a stranded cord, a practical holder must be provided which will apply the proper tension to the cord and be sufficiently rigid so that it may be easily handled to apply reciprocating frictional movement during the cleaning operation.

An object of this invention is to provide a cleaning implement or device which is efficient and compact and capable of removing foreign matter from the nails without affecting the sensitive parts of the fingers.

Another object of the invention is to produce a nail floss holder which can be manufactured at low cost and of convenient size to fit into a carrying case.

A further object of the invention is to combine a carrier or supply container in the holder to continuously supply the cleaning surface of tensioned material as often as needed.

In accordance with this invention the nail cleaning appliance comprises a holder having a body portion which can easily be gripped between the fingers and thumb to apply reciprocating movement to the holder.

The body portion is provided with arms at

the ends which are slotted to receive a stranded cord floss or other fibrous material treated with cleaning powder. The rigidity of the arms in spaced relation hold the cleaning floss under a suitable tension and when manipulated by the movement under the nails of the fingers removes every particle of foreign matter without irritation of the sensitive nerves of the finger and imparts a clean and fresh appearance to the nails. In another embodiment of the invention the body portion is formed into a hollow receptacle to receive a supply of floss which may be continuously wound over wedging buttons formed on the arm portions.

Another feature of the invention relates to a folding type holder having two sections of the same configuration, either section rotating in an arc about an axis of a circular body portion forming the floss receptacle. The floss receptacle is provided with symmetrical tapered arms which are in alignment in a closed position to form a compact structure and in an open position are locked in spaced relation by an abutting ear and the length of floss tensioned between the arms. This arrangement insures a convenient holder which occupies a small space yet may be easily adjusted to an operating position with a simple rotating motion. Furthermore, the elements of the holder being symmetrical can be manufactured at low cost and the assembly of the elements into a unitary structure can be accomplished with the minimum of press operations.

These and other features of the invention will be more clearly understood from the following detailed description in connection with the accompanying drawings.

Fig. 1 represents the simplest form of the nail floss holder made in accordance with this invention in which the spaced arms are slotted to receive the treated floss material shown above the holder.

Fig. 2 illustrates another form of rigid structure in which the body portion is a hollow cylinder enclosing a supply of floss adapted to be continuously fed into operating position.

Fig. 3 is an end view of the holder of Fig. 100

2, the holder being formed of a single blank of sheet metal.

Fig. 4 illustrates the folding or collapsible type holder made in accordance with this invention in which the two symmetrical portions may be closed for compactness and opened by rotating in an arc, with a cylindrical receptacle for the floss.

Fig. 5 is a cross-sectional view of the holder shown in Fig. 4 illustrating the simplicity of assembly.

Fig. 6 shows another form of the invention similar to Fig. 4, and

Fig. 7 illustrates in cross-section the arrangement of the two elements of the holder in Fig. 6 in which the two halves of the receptacle form the rotating surfaces for adjusting the holder to closed or open position.

Referring to the drawings, the nail cleaning floss holder of this invention in its simplest form comprises, as shown in Fig. 1, a unitary device formed of a single blank of sheet metal. The holder has a body portion 10 adapted to be gripped between the tips of the fingers and the thumb. Projecting from the ends of the elongated body portion 10 are integral arms 11 and 12 shown inclined outwardly from the center of the body portion 10. The arm 11 is provided with a slot 13 extending in from the outer edge to receive and securely hold the knotted end 14 of a length of stranded fibrous material 15, such as twisted cotton cord or floss. The floss 15 is preferably loosely twisted and highly absorbent and is adapted to be treated with a cleaning solution containing soap, chalk or whiting and thoroughly dried. After the knotted end of the floss is secured in position the length of floss is stretched taut between the arms 11 and 12 and inserted in the vertical slot 16 in arm 12 and wound around the reduced end of arm 12 formed by the slot 16 and the cut out portion 17. The arms 18 of the holder are quite rigid, therefore, the length of floss extending therebetween is held under a suitable tension whereby any desirable pressure may be exerted on the floss depending on the amount of foreign matter to be removed from the nails. When the floss is stretched between the arms of the holder it is desirable to moisten the floss by dipping in water or the floss may previously be treated with hygroscopic chemicals which cause the floss to absorb moisture from the air. This improves the dislodging qualities of the floss and aids in releasing the cleaning material held in the fibers of the material. In order to proceed with the cleaning of the nails of the hand it is only necessary to place the tensioned length of floss held in the arms 11 and 12 of the holder under the nail and apply reciprocating movement to the holder to remove encrusted foreign material under the nail. This motion applied to the floss

cleans the nail and at the same time releases the cleaning material held in the floss whereby the nails are cleared of dirt and grime and improved in appearance by the cleaning powder deposited under the nails.

Figs. 2 and 3 show the same type of nail cleaning appliance as Fig. 1 except the body portion is provided with a tubular receptacle 18 formed integral with the body portion 10 and the arms 11 and 12. The receptacle 18 is formed from an apron extension of the body portion which is folded over to form a cylinder directly below the body portion and extends over the upper edge of the body portion and folded at 19 to complete the press operation. The ends of the cylindrical receptacle 18 are closed by metallic caps or plugs 20 and 21, the cap 21 having an aperture through which a length of floss may be withdrawn from the supply of continuous floss 22 held in the receptacle. The arms 11 and 12 are provided with metallic buttons 23 over which the length of floss is tensioned. As shown in Fig. 2 the floss is wound around the buttons to securely wedge the floss in place and prevent slippage. A cutting edge 24 is provided on the inner edge of the arm 11 to sever the length of floss after cleaning the nails and removing from the wedging buttons. This can be accomplished in an expeditious manner after securing the following length of floss in position whereupon the soiled length may be cut off. This arrangement provides a compact and efficient device which may be conveniently carried in a handbag and used whenever desired. While the arms are shown in a plane coincident with the axis of the cylindrical receptacle 18 it may be desirable to arrange one or both arms at right angles to the body portion to secure flexibility in the device.

While the holders shown in Figs. 1 and 2 are rigid in structure to simplify the assembly, it is also within the scope of this invention to provide a holder of the collapsible type as shown in Fig. 4. In this embodiment the holder is formed of two elements substantially symmetrical in form having circular body portions 25a and 25b and tapered arms 26a and 26b. The circular portions are held in face-to-face relation and riveted together at the center as shown clearly in Fig. 5. The element formed by the circular portion 25a and arm portion 26a is a substantially flat blank while the other element is provided with a discontinuous upturned edge 27 extending around the outer boundary of the circular body portion 25b. This is shown in dotted outline in Fig. 4. The arm portion 26b is bent outwardly at 28 and then parallels the arm portion 26a but in spaced relation thereto. Attached to the ends of the arms are the wedging buttons 23 arranged in opposed relation and protected in the closed position of the holder to prevent interference with loose ar-

ticles in the handbag. The receptacle for containing the supply of nail cleaning floss is formed in accordance with this invention by a cup-shaped cap or cover 29 which embraces and securely fits on the upturned edge 27 of the cylindrical portion 25b. The cover is provided with a slot or opening 30 in alignment with an aperture 31 in the bent portion of the arm 26b through which a length of floss from the receptacle may be drawn to be tensioned between the buttons on the arms of the holder. The holder is shown in operating position in Fig. 4 with the arms held in spaced relation by a stop member 32 which is an upturned lug projecting from the edge of the arm 26b adjacent the circular body portion 25b. This stop member limits the rotation of the flat element when it is desired to employ the holder for cleaning the nails and also limits the rotation of this element in the direction indicated by the arrow in the collapsed position of the holder as shown in dotted outline. This form of holder requires a small amount of space yet is easily adjusted for use. Furthermore, the structure is substantially rigid and can be easily manufactured at low cost.

The structure shown in Figs. 6 and 7 is a modified form of the invention described above and consists of two elements in which the circular body portions 25a and 25b are provided with cups or cover members 33 and 34 which are fitted together as shown in cross section in Fig. 7 to form the receptacle for the nail cleaning floss and act as a rotating bearing for the holder. The arm portions 26a and 26b are bent close together in face-to-face relation and the wedging buttons 23 are attached to the outer surfaces of the arms. A stop member 32 limits the movement of the arms in the same manner as described in connection with the holder shown in Fig. 4. This arrangement permits the assembly to be accomplished with substantially similar elements which can be manufactured at a cost lower than the structure shown in Fig. 4. Furthermore, the rotation of the arms is considerably freer due to the receptacle which forms the bearing surface for rotating the arms into either closed or open position.

The invention has been disclosed in which the holders are formed of metal which is a desirable material to handle in manufacturing process and may be easily colored in attractive shades to appeal to feminine tastes. Furthermore, the flat surface of the body portion of the holder provides space for printing or advertising display. However, it is to be understood that the invention may also be applied to other materials such as "bake-lite" or other moldable material.

Various forms of the invention are shown in the drawings and described in the specification but the invention is not to be limited to these specific forms since it is readily ap-

parent that various modifications may be made without departing from the scope of the invention as defined in the appended claims.

What is claimed is:

1. A nail cleaning device comprising two symmetrical elements having a body portion and an arm extending portion, means for rotating said elements in an arc, and means forming a receptacle carried by said body portions of said elements. 75

2. A nail cleaning device comprising two symmetrical elements having a body portion and an arm extending portion, means for rotating said elements in an arc, means forming a receptacle carried by said body portions, 80 and means projecting from one of said elements and abutting against the other element to limit the rotation thereof.

3. A nail cleaning device comprising two symmetrical elements having a circular body portion and an arm extending portion, means for rotating said elements in an arc, one of said elements having an upturned edge around the periphery of the circular body portion, and a cap member fitting over said 90 edge. 85

4. A nail cleaning device comprising two symmetrical metallic elements having a circular body portion and an arm extending portion, the two circular portions being centrally riveted together and rotatable with respect to each other, the arm portions being positioned in parallel spaced relation, and wedging means formed on the ends of said arms and located between the spaced ends 100 thereof. 95

5. A nail cleaning device comprising two symmetrical elements having a circular body portion and a tapered arm portion projecting from said body portion, the two circular portions being joined together centrally and rotatable in an arc, said arms being spaced in parallel relation, and metallic buttons rigidly fastened to the ends of said arms. 105

6. A nail cleaning device comprising two similar shaped elements joined together and rotatably movable adapted to be positioned in alignment in closed position and capable of being adjusted to open position with the free ends spaced, and means carried by the joined 110 ends for feeding cleaning floss to the free ends of said elements to tension a length of floss therebetween. 115

7. A nail cleaning holder comprising two similar shaped metallic elements having circular body portions and arm extensions, said body portions being in spaced relation and the arm portions in contact with each other in closed position, and means carried by said body portions forming a receptacle therebetween and serving as a circular bearing for 120 rotating said elements. 125

8. A nail cleaning holder comprising two similar shaped metallic elements having circular body portions and arm extensions, said 130

body portions having cooperating circular rims adapted to interlock to form a receptacle for cleaning floss, and means attached to said arms for tensioning the floss in operating position.

9. A nail cleaning holder comprising two similar shaped metallic elements having a circular body portion and an arm extension, and a cup-shaped member joined to the inner surface of each of said body portions.

10. A nail cleaning holder comprising two symmetrical metallic elements having a circular portion and an arm extension integral therewith, and a cup-shaped member centrally riveted to each of said body portions, the edge of one of said members fitting within the other member to form a friction bearing for rotating said elements with respect to each other.

11. A nail cleaning holder comprising two symmetrical metallic elements having a circular body portion and an arm extension integral therewith, a cup-shaped member attached to and within the boundary of each of said body portions and adapted to be interlocked to form a friction bearing for said elements, wedging buttons carried on the ends of said arms, and means projecting from one of said arms limiting the rotary movement of the other arm in either direction.

In witness whereof, I hereunto subscribe my name this 17th day of July, 1930.

ERNEST SORENY.
